UNITED STATES PATENT OFFICE.

PAUL A. BRATTAIN, OF SEATTLE, WASHINGTON, ASSIGNOR OF ONE-HALF TO PLINY T. BRICHARD, OF SEATTLE, WASHINGTON.

DISPLAY CARD.

Application filed September 30, 1925. Serial No. 59,446.

To all whom it may concern:

Be it known that I, PAUL A. BRATTAIN, a citizen of the United States, and resident of Seattle, King County, Washington, have 5 invented certain new and useful Improvements in Display Cards, of which the following is a specification.

My invention relates to display cards and particularly to the type which is intended 10 for association with an article of merchandise.

The principal object of my invention is to produce a display card of this type so constructed that it may be securely held in 15 place by the article itself. It is also an object to produce a card of this type which may be more cheaply made than the cards generally used for this purpose, particularly through the elimination of a separate easel 20 back or of easel or supporting attachments for the card.

Still another object is the provision of such a card which can have an interlocking engagement with the article so that the two 25 may not be readily separated, and so that the card may not be upset except as the article itself is upset.

My invention consists in producing a card of this kind having a hole for the reception 30 of the article of merchandise, the outlines of which hole shall be such as to accommodate the article of merchandise and to permit it to be passed, partially at least, therethrough and at the same time to form an 35 overlapping or interlocking engagement with the merchandise, preferably towards the top and bottom thereof, but at least towards the top, which will prevent the card from falling down.

40 The particular features of construction which form the novelty in my invention will be hereinafter described, and the novel combinations upon which I desire to secure patent protection will be particularly defined 45 in the claims.

In the accompanying drawings, I have illustrated my invention as constructed for application to packages of various shapes and sizes.

50 Fig. 1 represents a blank, such as would be used for application to a round can;

Fig. 2 represents the same card applied to the can, or as it would be used in display;

55 Fig. 3 is an edge view of the same card applied to a can;

Fig. 4 shows a face view of the blank cut for use in connection with a bottle;

Fig. 5 is a front or face view of the same card as applied to a bottle; and Fig. 6 is an 60 edge view of the same;

Fig. 7 shows a blank adapted for application to a rectangular package;

Fig. 8 is a face view of the same card, shown applied to its package;

Fig. 9 is a face view of a card shown applied to a rectangular package in which the package is shown with a face of the package presented fully to the front, instead of the package being placed in diagonal relation thereto, as it is in Fig. 8. 70

In preparing a card for display purposes, I prefer that it be formed with a base section as 1, folded back along the scored line 10 to form a base upon which the package is designed to rest. An opening is made in 75 the card, the shape and size of which may vary widely but which would ordinarily correspond fairly closely to the outline of the package with which it is to be used. The opening shown in the card of Figures 1, 2 80 and 3 has curved vertical sides, the central portion of this opening, measured horizontally, being at least of a width corresponding with the horizontal diameter or over-all measurement of the package from 85 its top down to and including its height.

The top of the opening is of less extent than the horizontal dimension of the package and, in fact, is less than the least diameter of the top of the package. 90 The purpose of this is to have the upper portion above the greatest width of the opening (say at the point 20) of less width than the upper portion of the package. Preferably, also, the same is true at 95 the points 21 toward the lower end of the opening, that is to say, they are spaced less than the width of the package at this point. These portions at the top and the bottom of the opening are designed to overlap the outline of the package at the top and bottom thereof, respectively. In addition to this, 100

and solely for convenience of application of the card to the package, it is desirable to have a portion of the base cut away, as shown at 22, whereby a projecting corner of the package is cleared as the base 1 is swung backward. Without this, it may at times be difficult to apply the card to the package. 105

The appearance of the card, as applied to a package of the type for which the card of Figures 1 and 2 is designed, is shown in Figures 2 and 3, the portion 20 of the upper part of the opening, which is constructed or made of less distance across the opening than the width of the package, is shown as extending along the sides of the package towards the rear part thereof, while the corresponding portions 21, at the bottom of the opening, are shown as extending over the face of the package to a limited extent.

The position of the card with relation to the package, as seen in an edge view of the card, is shown in Figure 3. It will be observed that the plane of the card intersects the general vertical axis of the package at a level between its top and bottom. A card so positioned will engage the sides of the package above this point of intersection to prevent forward movement of the card. The top of the package is engaged by the upper edge 23 of the opening, and this prevents backward movement of the card relative to the package. By reason of these two engagements, therefore, the card is prevented from falling either forward or backward so long as the package 24 is not itself displaced.

Preferably, however, the side edges 21 of the opening engage the side face of the package from the front, that is, below the point of intersection of the plane of the card and the general vertical axis of the package, whereby forward movement of the package relative to the card, such as might occur were the package to be slid forward, is prevented. This engagement of the edges 21 with the package likewise supplements the action of the edge 23 in preventing tilting backward of the card, and, in fact, with light cards, might altogether replace this engagement for the purpose. By reason of the engagement of the side edges 20 with the side face of the package from the rear, and by reason of engagement of the edges 21 with the side face of the package from the front, the package and card are interlockingly engaged so as to prevent falling down of the card, whether forwardly or backwardly.

The card illustrated in Figures 4 and 5 is designed for application to a bottle. The principle of construction used in outlining the opening which is to receive the bottle, is the same as that for a can. The upper part of the opening, corresponding in position with the neck of the bottle, has its sides inclined towards each other so that at its upper end the parts are separated a distance less than the diameter of the bottle neck, while at the bottom of the opening the sides are drawn together to a distance less than the diameter of the base of the bottle. The upper edge of the opening, as at 23, for both

of these cards, will rest upon the upper end face of the package. The base section 1 by forming a support for the package, securely holds the card against being tipped over by wind or any light force.

In Figures 7 and 8, I have shown a card adapted for application to a rectangular package and the manner in which the package is associated therewith. This card has been designed for holding the package in a position in which the faces of the package are diagonal or inclined to the face of the card. The short section 30 of the opening in the card engages the upper end face of the package. The inclined portion 31 engages one of the vertical faces of the package, while the other inclined edge 32 engages a vertical face of the package which is at right angles to that engaged by the edge 31. The inclined face 33 engages a face of the package opposite to that engaged by the edge 31, and the edge 34 engages a face of the package opposite to that engaged by the edge 32. In this case also it is desirable that the notch be extended into the base section a short distance, as is shown at 35, this being done merely for convenience in applying the card to the package.

In Figure 9, I have illustrated how a card may be applied to a rectangular package and have the front plane of the package square with relation to the card, that is, the front face of the card and the front face of the package intersect upon horizontal lines adjacent to the base. In this case the outline of the opening in the card might have short sections, as 40, inclined somewhat both to the top and the side edges of the opening, it being intended that these should overlap, respectively, with the front and the rear face of the package.

The openings cut in the card may be broadly defined as being the outline formed by the package on a plane which is diagonal with the package and which, in all of the forms except that shown in Figure 9, intersects the top and bottom faces of the package at points adjacent, respectively, to the front and the rear face of the package. In the modification shown in Figure 9, the full width shape of the opening stops a little short of the top and bottom of the package. This may be done by a diagonal cut, as shown in Figure 9, or by any other suitable cut, as, for instance, by extending the upper edge horizontally at points which run a little short of the top and bottom, respectively.

It will be understood that the edges of the cut intermediate the portions 20 and 21, if the latter are employed, need not closely embrace the package. Indeed, for many displays it may be found desirable to cut the card away between these engaging portions so that the package may be more fully

displayed: This is well within the scope of my invention. It will be understood also that the principle herein disclosed can be applied to packages or objects of widely varied shapes, in fact, of any shape except a perfect sphere. A perfect sphere cannot be so supported only because all of its diameters are equal. For any shape wherein two diameters are unequal, the principles of the present invention may be employed to support it in a display card. By so supporting it, and with the package resting upon the base section of the card, the card is securely held against any ordinary accidental displacement.

What I claim as my invention is:

1. A display card for use with merchandise packages having a hole cut therein of a shape and size that its side edges will fit a diagonal outline of the package, and its top edge will engage the top of the package when positioned in the hole, said card having a base section adapted to fold under the package and having a shallow cut therein to facilitate insertion of the package.
2. A display card for packages having a base section adapted to fold back and a hole cut in the main body of a shape to fit the package upon the outline formed by a diagonally intersecting plane which cuts across the top and bottom ends of the package in-

ward from and adjacent to respectively the back and the front sides of the package, said hole having an extension which cuts into the base to thereby facilitate placing of the package in the hole.

3. A display card for association with a package comprising a sheet having a package-receiving aperture, the aperture, below its upper edge, being of a width not less than the width of an intermediate portion of the package, whereby the package may be received in said aperture within the plane of the sheet, the side edges of the aperture, above and below the intersection of the plane of the sheet with the general vertical axis of the package, being of less width than the corresponding width of the package at corresponding heights, whereby the upper side faces of the package are engaged thereby from the rear to prevent the sheet falling forward, and whereby the lower side faces of the package are engaged thereby from the front to prevent the sheet falling backward, and a base section hingedly connected to the lower edge of the sheet in the line of the lower edge of the aperture, and adapted to be folded back, whereby the package may rest thereon, the base section being cut out in a continuation of the aperture in the sheet to permit insertion of the package.

PAUL A. BRATTAIN.
